United States Patent Office

Des. 186,267
Patented Oct. 6, 1959

186,267

SHOE

Albert Zerkowitz, New York, N.Y.

Application April 17, 1959, Serial No. 55,553

Term of patent 14 years

(Cl. D7—7)

Fig. 1

Fig. 2

Fig. 3

Fig. 4

Fig. 1 is a side elevational view of a shoe, showing my new design;

Fig. 2 is a bottom plan view;

Fig. 3 is a longitudinal sectional view taken on line 3—3 of Fig. 2; and

Fig. 4 is a transverse sectional view taken on line 4—4 of Fig. 2.

The dominant features of the design reside in those portions shown in full lines in the drawing.

I claim:

The ornamental design for a shoe, as shown and described.
